CLAIM

The ornamental design for an exercise grip device, as shown and described.

DESCRIPTION

FIG. 1 is a front side elevational view of the exercise grip device of the present invention;

FIG. 2 is a rear side elevational view thereof;

FIG. 3 is a top down view thereof;

FIG. 4 is a bottom up view thereof;

FIG. 5 is a left side elevational view thereof;

FIG. 6 is a right side elevational view thereof; and,

FIG. 7 is a front side elevational view of the exercise grip device in an open configuration.

The broken lines in the drawings represent claimed stitching which forms part of the claim.
